VENTILATOR GRILLE

Raymond V. Pfautsch, Chicago, Ill., assignor to Ilg Electric Ventilating Co., Chicago, Ill., a corporation of Delaware

Application April 15, 1950, Serial No. 9,256

Term of patent 14 years

(Cl. D62—4)

To all whom it may concern:

Be it known that I, Raymond V. Pfautsch, a citizen of the United States, residing at Chicago, in the county of Cook and State of Illinois, have invented a new, original, and ornamental Design for a Ventilator Grille, of which the following is a specification, reference being had to the accompanying drawing, forming part thereof:

I claim:

The ornamental design for a ventilator grille, substantially as shown.

RAYMOND V. PFAUTSCH.
